1

This invention pertains to the conversion of high boiling hydrocarbons to valuable lower boiling products. It is particularly concerned with a process for the cracking conversion in the presence of solid contact mass materials of high boiling liquid petroleum fractions which undergo thermal decomposition below temperatures at which they will vaporize.

It is well known that vaporized petroleum gas oils and the like may be converted to lower boiling products containing high antiknock gasoline by contacting the gas oil with adsorbent catalysts at temperatures of the order of about 800° F. and upwards and pressures usually of the order of 5 to 100 pounds per square inch gauge. It is also known to similarly convert higher boiling petroleum fractions which exist in the liquid phase under the cracking conditions. However, in the latter case, the amount of coke material deposited on the catalyst during the cracking reaction is very high, particularly in the case of stocks having high carbon residues such as petroleum residua. In many cases the amount of coke deposit on the catalyst, which must be removed by burning in order to maintain the catalyst activity is so high as to render the catalytic cracking of petroleum residue charges economically unfeasible. It is usually the practice to subject such petroleum residua to a preliminary coking, tar separation or viscosity reducing treatment prior to use as a catalytic cracking charge stock. Often even in these operations, the gasiform stream from the coking vessel, for example contains substantial amounts of entrained liquid hydrocarbons having a very high carbon residue content. These streams cause serious coking on the walls of the coking vessel near the gas outlets and in the transfer lines leaving the coking unit and also in any heating furnace through which they may pass prior to introduction into a catalytic cracking reactor. Also, the entrained liquid in the gasiform stream from the coking unit may result in undesirable heavy coke deposits on the cracking catalyst thereby largely defeating the purpose of the coking or tar separation operation.

It is a major object of this invention to provide an improved process whereby high boiling liquid petroleum fractions may be converted to high antiknock gasolines while avoiding the above mentioned difficulties.

Another object of this invention is the provision of an improved process for conducting coking conversions of petroleum residua to provide lower boiling vaporizable products having low carbon residue contents.

2

A specific object is the provision of a novel continuous process for pyrolytically and catalytically converting petroleum residua and the like to gasoline containing products in the presence of suitable solid contact materials. These and other objects of this invention will become apparent from the following description thereof.

This invention in its preferred form involves a method wherein the high boiling liquid hydrocarbon charge, for example a petroleum residuum is introduced into the lower section of a compact column of granular inert heat carrying material to become converted pyrolytically to a gasiform intermediate product which may contain small amounts of entrained non-vaporized liquid hydrocarbons. The intermediate product is then passed upwardly through the column until it contacts cooler heat carrying material by which it is quenched to a temperature at which the pyrolytic reaction is substantially inhibited and the entrained liquid is deposited onto the heat carrying material. In some operations, a small percentage of the intermediate product may be condensed and also deposited upon the contact material. The deposited liquid subsequently breaks down to coke and gasiform product in the lower portion of the column. The cooled gasiform intermediate product substantially free of entrained liquid hydrocarbons is then heated to a suitable catalytic cracking temperature and passed into contact with a suitable adsorbent catalyst to effect its conversion to a product containing high antiknock gasoline. A stream of heated inert heat carrying material is passed from a separate heater into the lower section of the column to supply the heat required for the pyrolytic conversion of the liquid hydrocarbon charge. A second stream of the same heat carrying material is supplied to the column at a higher level than the first stream and at a lower temperature so as to effect the quenching of the intermediate reaction product. According to one form of this invention, a third stream of heat carrying material is supplied to the column at a still higher level and at a temperature intermediate those of the first and second streams to effect heating by direct heat exchange of the quenched intermediate product to the catalytic cracking temperature. Used heat carrying material is withdrawn from the bottom of the column to cause downward movement of the granular material in the column.

The inert granular material employed in the process of this invention should be a solid material having a relatively low or substantially no catalytic cracking activity, a high heat absorp-

tion capacity and it should be capable of withstanding high temperatures of the order of 1500° F. without severe breakage, cracking or attrition. The material may be non-porous, for example metallic pieces or balls. Preferably however, the solid material should be porous, for example natural clays which have become deactivated so as to have a very low activity as a cracking catalyst. Other materials which may be employed are pumice, mullite, fused alumina, silica, etc. A preferred heat carrying material is granular petroleum coke. The granular material may range in size from about 100 mesh Tyler up to about one inch in diameter and preferably of the order of one-eighth to one-quarter inch diameter. The term "granular" is employed herein in a broad sense as including solids in various shapes and forms such as pellets, tablets, spheres and irregular shaped particles.

The catalyst employed for the final catalytic cracking step may partake of the nature of natural or treated clays, bauxites and the like or synthetic associations of silica, alumina, magnesia or silica and alumina or silica and magnesia to which other metallic oxides may be added for special purposes. The catalyst may be in the form of a powder in which event it may be maintained in suspension in the reaction zone. On the other hand, the catalyst may preferably be in the form of granular particles having average diameters within the range about 4 to 100 mesh Tyler and preferably 4 to 20 mesh.

The invention may be more readily understood by reference to the attached drawings of which Figure 1 is an elevational view, partially in section, of one form of an arrangement for conducting the invention; Figure 2 is a similar view of a preferred form of the invention and Figure 3 is an elevational view, partially in section, of a modification of part of the arrangement shown in Figure 2. All of these drawings are highly diagrammatic in form.

Turning now to Figure 1, there is shown a vertical vessel 10 which may be of any convenient cross sectional shape. An outlet conduit 11 for solid material withdrawal is provided at the bottom of vessel 10 and a row of liquid inlet pipes 12 connect into the lower section of the vessel. Suitable spray devices 13 are connected to the pipes 12. Liquid charge may be supplied into pipes 12 from manifold 45 and conduit 46. A heating chamber 15 and heat exchange chamber 16 are positioned above the vessel 10. The chambers 15 and 16 are provided with solid material inlets 17 and 18 respectively at their upper ends and solid material outlets 19 and 20 respectively at their lower ends. An air inlet 14 connects into the lower section of heater 15 and may communicate within the heater with gas distributors (not shown). A flue gas outlet 113 is provided near the top of the heater. Heat transfer tubes (not shown) may be provided within the heater and a suitable heat exchange fluid such as water or steam may be supplied to these tubes via inlet 21 and withdrawn therefrom via outlet 22. Any suitable form of kiln adapted for burning of carbonaceous deposits from solid contact material may be substituted for the heater 15. In some operations, the heating may be accomplished by means of combustion of a fluid fuel within the heater in which event a mixture of air and fuel may be supplied via inlet 14. The chamber 16 is adapted for either heating or cooling the solid material depending on the particular operating conditions involved. The solid material may be

cooled or heated within chamber 16 by direct contact with a suitable cooling or heating gas such as flue gas or steam supplied at 23 and withdrawn at 24. Optionally, the cooling or heating may be accomplished by indirect heat transfer or by spraying a liquid onto the bed of solids in the cooling vessel.

In many operations the amount of contaminant deposit on the heat carrying material may be satisfactorily regulated by burning off the contaminant only from the material passed through heater 15. In other operations, it may be desirable to subject all of the circulating heat carrying material to burning in which event a suitable kiln may be provided in the line of pipe 18 prior to the exchanger 16. Alternatively, all of the material may be passed through vessel 15 after which a portion is diverted to vessel 16 for temperature regulation.

The exchanger 16 communicates with the upper section of vessel 10 via conduit 20 and branch pipes 26 which may be several in number. The heater 15 communicates with a lower section of vessel 10 through conduit 19 and branch pipes 29. The ends of pipes 29 are provided with flared members 30 to aid in the discharge of solids into the bed of heat carrying material. A separate catalytic cracking system 27 is also provided and is connected through conduit 31 and heater 32 and conduit 33 to the upper part of vessel 10.

In operation, a substantially compact column 40 of granular heat carrying material, for example petroleum coke, is maintained within vessel 10. Coke is withdrawn from the bottom of vessel 10 at a suitable rate controlled by valve 41 on outlet 11. Prior to its withdrawal, the coke is purged substantially free of gasiform hydrocarbons by means of an inert purge gas such as steam or flue gas supplied through conduit 70. Part of the used coke bearing a coky deposit formed during the pyrolytic conversion reaction is passed via conveyor 36 and conduit 17 into heater 15 wherein it is heated by combustion of all or part of the coky material deposited by the hydrocarbon conversion. In an exemplary operation, the coke may be heated from a convertor outlet temperature of about 800° F. to about 1100° F. at which temperature it is introduced into the lower section of column 40. The rate of heated coke supply may be controlled by means of slide valve 53 operated by rod 54 from a location outside the vessel or by other suitable means. A seal chamber 55 is provided on the conduit 19 to prevent escape of hydrocarbons. Steam may be supplied to the seal chamber via pipe 56. A petroleum residuum charge which may have been preheated to about 600° F. is introduced via conduit 46 and pipes 12 and spray devices 13 into the column 40 at a level shortly below the level of heated heat carrying material introduction. The liquid oil is distributed uniformly onto the granular coke and heated thereby so as to effect pyrolytic cracking conversion to a lower boiling intermediate product existing in the gaseous phase except for a small amount of entrained non-vaporized liquid hydrocarbons. A coky contaminant is deposited on the heat carrying material during this reaction. The gasiform intermediate product and entrained liquid hydrocarbons pass upwardly through column 40 to be subjected to increasingly higher temperatures until the level of spreaders 30 is reached. Thereafter, the intermediate product is quenched to a substantially lower temperature by contact with the cooler coke supplied from chamber 16 via con-

duit 28. The solid material entering from conduit 20 may be at a temperature of about 850° F. for example. This material constitutes the remainder of the used material withdrawn from the bottom of vessel 10 at 800° F. and is heated to 850° F. in exchanger 16. The rate and temperature or the rate alone of introduction of the heat carrying material onto the surface of column 40 is controlled so as to cool the intermediate product to a temperature at which the coking or pyrolytic reaction is substantially inhibited, and at which the entrained liquid hydrocarbons are deposited on the heat carrying material. If desired, the quench temperature may be sufficiently low to condense up to about 15 percent of the gasiform intermediate product, the higher boiling constituents being condensed. It is undesirable to condense substantially more than about 15 percent of the product and preferably the amount of intermediate product condensed and deposited on the heat carrying material should be limited below about 5 percent. Usually, the intermediate product is cooled in the quenching zone at least 25-100° F. below the maximum temperature which it reaches in the coking zone. The liquid deposited on the heat carrying material is carried thereby down into the hotter zone below flared members 30 and is eventually cracked down to coke and lower boiling gasiform hydrocarbons. The term "gasiform" is used herein in a broad sense as covering material in the gaseous phase under the particular conditions of pressure and temperature at which it is present regardless of what may be the normal phase of the material under ordinary atmospheric conditions. The quenched gasiform intermediate product is withdrawn from the upper section of vessel 10 via conduit 33 at a temperature of 850° F. for example and may be passed directly to the catalytic cracking system 27 or heated first to about 900-950° F. and then passed to the catalyst reactor. The intermediate product is converted in the catalyst reactor to a lower boiling product containing high antiknock gasoline. Since the entrained liquid hydrocarbons, which have a high residual carbon content are left behind in the vessel 10, the conversion of the petroleum residuum to high antiknock gasoline is accomplished without incurring excessively high coke deposits on the catalyst. Also, since the entrained high carbon residue liquid has been removed in that portion of vessel 10 wherein the granular heat carrying material is flowing, the deposition of coke on the walls of the vessel near the outlet and in the transfer line 33 is avoided. When the catalytic cracking system is not in operation the intermediate product from vessel 10 may be withdrawn to storage via conduit 60. The used heat carrying material is conveyed by a suitable conveyor 36 or gas lift to a level above chambers 15 and 16 and then passes in part to each stream as controlled by valves on conduits 17 and 18. When a material other than petroleum coke is employed as the heat carrying material, the amount of carbonaceous material thereon should be maintained at a low constant value by burning with a combustion supporting gas in heater 15, and if necessary, in an auxiliary kiln inserted before chamber 16. If the heat transfer material is petroleum coke, only so much of the coke deposit thereon need be burned off as will meet the heat requirements of the cyclic system. If the amount of coke in the system builds up it may be withdrawn as a by-product via conduit 200. Inert gas seal zones 55 and 55' are provided on conduits 19 and 20 to prevent escape of

hydrocarbons from vessel 10 into the chambers 15 and 16. It is not essential that chambers 15 and 16 be positioned above the vessel 10 as long as a suitable means is provided for solids transfer from chambers 15 and 16 to the proper levels in vessel 10.

In most operations the desired quench temperature is below that required for the catalytic cracking reaction and in such operations it is preferable to employ the arrangement shown in Figure 2 of the drawings. In Figures 1 and 2, equivalent elements bear similar numerals and need not be further described. In the arrangement shown in Figure 2 the heated heat carrying material from heater 15 passes via conduit 80 into a seal chamber 81 provided in the upper section of vessel 82. Part of the heated solid material passes via tubes 84 onto the surface of column 40 and the remainder passes via tubes 85 into the lower section of the column. Slide valves 86 are provided for rate control. Cooled solid material passes from cooler 16 via conduit 87 and tubes 88 into the column at an intermediate level. Flared members 89 and 90 are provided on the lower ends of tubes 85 and tubes 88 respectively. Baffles 90 may be provided below flared members 90 to insure uniform mixing of the solid material from tubes 88 with the solids flowing down from the upper portion of the column. In a typical operation heated solid material may be supplied through tubes 85 and 84 at about 1200° F. Cooled solid material may enter the column from tubes 88 at 700° F. Liquid hydrocarbon charge may be supplied from conduit 91, pipes 92 and nozzles 93 into the column below the level of hot heat carrying material introduction. The liquid charge is converted in the coking zone A by means of the heat supplied by the heat carrying material. The intermediate conversion products carrying entrained non-vaporized liquid hydrocarbons pass up through the column to be cooled in the quench zone B which lies between the levels of flared members 89 and 90. The quenched vapors at about 750° F. then enter the preheating zone A which occupies that portion of the column above flared members 90. In the preheating zone the vapors are heated to a suitable catalytic cracking temperature, for example 850° F. and are then disengaged from the column surface and passed via conduit 33 to the catalytic reactor 25. The rate of supply of heated heat carrying material to the preheating zone may be controlled by means of plug valves 96 to provide the desired vapor outlet temperature. The rate of hot solid material supply to the coking zone may be controlled by slide valves 86 and the cool solid supply to the quench zone may be controlled by valve 91. Downward movement of the heat carrying material through all of the zones is accomplished by withdrawal of the used heat carrying material from the bottom of the vessel through conduit 11. This causes the heat carrying material from the zone A to join that supplied from tubes 88 into zone B and the material from zone B joins that supplied from tubes 85 into zone C. A preferred method of operation is to set the valves 91 and 86 so as to allow the proper proportions and amounts of cool and heated solid material to enter zones B and C respectively and to set the valve 41 on outlet 11 to permit withdrawal via conduit 11 of an amount of solid material which is in excess of the total of the solids supplied via pipes 88 and 85 by an amount corresponding to the requirements of zone A. Pipes 84 then need not be throttled so that

they serve to control the column surface level constant. Uniform flow and purging of the granular solid material may be accomplished by an orifice plate arrangement as shown in Figure 2. This arrangement is claimed and described in United States Patent 2,434,202 issued January 6, 1948. The catalytic reactor 95 may preferably be of the moving bed type which is described in United States Patent 2,419,507, issued to Simpson et al. on April 22, 1947. Adsorbent catalyst in granular form passes downwardly through the reactor 95 and is contacted by the rising petroleum vapors which are converted to a gasoline containing product. The gasiform product is withdrawn via conduit 105. The form of the invention shown in Figure 2 offers several important advantages. It permits the preheating of the intermediate gasiform product to the catalytic cracking temperature within the same vessel and column of solid material that is employed for the pyrolytic conversion, thereby eliminating the need for a separate furnace. Moreover, the heat required for the preheating is supplied from within the coking system by burning formed coke, thereby effecting a saving in heating fuel requirements. In addition, the quenched stream from zone B is heated to a level substantially above its dew point in zone A thereby eliminating the danger of heavy oil condensation in the upper part of vessel 82 and in the transfer line 33. If there is any tendency for coke formation during the preheating step, it is deposited on the heat carrying material and not in the tubes of a preheating furnace. As discussed above in connection with Figure 1, in some operations the heat carrying material introduction via tubes 88 into the quench zone may be introduced at a temperature slightly above that of the solid material discharged from the bottom of vessel 82 via conduit 11. In such operations, the chamber 16 may be operated as a heater. Also, in some operations the temperature of the used heat carrying material may be approximately that desired for the quench zone in which case the chamber 16 may be employed purely as a surge hopper in the cyclic system.

In order to permit greater flexibility of control in the preheating zone provision may be made for separate control of the temperature of the heat carrying material supplied onto the column surface. Such an arrangement is shown in Figure 3 which shows a modified portion of the arrangement in Figure 2, the rest of the arrangement remaining the same. In Figure 3, double supply chambers 107 and 106 are provided in the upper section of vessel 82 by means of horizontal partitions 101 and 102. Heated solid material from heater 15 (shown in Figure 2) passes down through conduit 80 which fits through partition 101 into the chamber 106 from which it passes via tubes 85 to the pyrolytic conversion zone. A part of the heated heat carrying material is permitted to flow from conduit 80 through pipes 110 into chamber 107 above partition 101. Conical valves 109 mounted on slide rods 111 are provided to control the rate of solid material flow from pipes 110. The rods 111 slide through bushings 112 which should be gas tight. The temperature of the solid material in chamber 107 is controlled by admitting cooler material from an external cooler via conduit 87 to 111. If desired, a separate exchanger (not shown) may be provided in which the solid supply for the preheating zone is regulated to the proper temperature level and then supplied into chamber

107 via conduits 112 and 111. In this case, the pipes 110 may be eliminated. Cooled contact material passes from a cooler through pipe 87 into the lower portion of a distributing zone 122 defined between spaced horizontal partitions 121 and 123. The contact material is delivered into the zone 122 from a confining cone 120 into which conduit 170 connects. Cooled contact material passes from zone 122 via a plurality of pipes 130 into the surface of the column 140 in a lower portion of the vessel. A gas withdrawal space 141 is provided around the pipes 130 and above the column 140. It will be noted that the hot contact material supply pipes extending down from partition 102 are positioned laterally between pipes 130 and terminate at a substantially lower level in the vessel than pipes 139, thereby providing for a quench zone in the upper portion of the column and a conversion zone therebelow. Liquid petroleum residuum is charged from manifold 152 and nozzle pipes 153 onto the column below angle baffles 154 at a level below that of the hot contact material supply. The vapors resulting from the coking reaction pass up through the cooler material in the quench zone 150 where they are quenched to inhibit further reaction and to effect condensation on the contact material of entrained liquid hydrocarbons. The quenched vapors pass from the gas space 141 via by-pass pipe 153 into distributor troughs 154 positioned in the bed 180 of contact material shortly above partition 123. The reactant vapors are then heated to a temperature suitable for effecting catalytic conversion thereof by means of the contact material entering from zone 107 at a suitable controlled temperature. Preheated vapors then pass via conduit 155 to the catalytic reactor. The contact material from the preheating bed 180 passes via pipes 157 onto the surface of column 140 at a temperature which is usually below that of the contact material supplied through pipes 85 but above that of the cooled material entering via pipes 130. Flow throttle cones 160 mounted on rods 161 which slide through bushings 162 are positioned below pipes 130. The cones may be raised or lowered by rotation of the eccentrics 165 mounted on shaft 166 below the Y-shaped end of rods 161. Slide valves 162 operated from the back side of the unit similarly to valves 86 of Figure 2 are mounted on pipes 85. By means of cone valves 160 and slide valves 162 the rate and relative proportion of heated and cool contact material delivery to the column 140 may be controlled. The valves are set so that the total of these two streams is less than the total contact material withdrawn from the bottom of the vessel. The differential is automatically taken up by the contact material flowing through open pipes 157 from the preheating bed 180. It will be noted that since the other two contact material streams are individually controlled by throttle valves, the rate of contact material flow from zone 107 onto the preheating bed 180 may be controlled by control of the rate of solid withdrawal from the bottom of the vessel and at the same time the stream from the zone 107 serves automatically to maintain constant the surface levels of bed 180 and column 140. The escape of hydrocarbons through the solid material feed pipes is prevented by introduction of a seal gas such as steam or flue gas via pipes 195, 196 and 197 at rates sufficient to maintain the inert gas pressure in the zones of its introduction slightly

greater than the reactant pressure in the bed 180 and column 140.

The particular operating conditions to be employed in the process of this invention vary over a wide range depending upon the original charge stock, the heat carrying material and catalyst employed and the desired severity of the pyrolytic cracking reaction. In general, the operation will fall within the following approximate ranges of temperature:

Contact Material Streams		
Entering Coking Zone.....	^o F.	Broad Range.
Do.....	800-1,500	Preferred Range.
Entering Quench Zone.....	950-1,150	Broad Range.
Do.....	100-1,000	Preferred Range.
Entering Preheating Zone.....	825- 900	Preferred Range.
Do.....	800-1,200	Broad Range.
Leaving Coking Zone.....	850-1,000	Preferred Range.
Do.....	700-1,400	Broad Range.
Leaving Catalytic Reactor.....	800-1,050	Preferred Range.
Do.....	800-1,200	Broad Range.
Leaving Catalytic Reactor.....	850-1,050	Preferred Range.
Do.....	775-1,000	Broad Range.
Fluid Streams:		
Charge to Coking Zone.....	Atmospheric to 800	Broad Range.
Do.....	500- 750	Preferred Range.
Charge to Catalytic Zone.....	800-1,050	Broad Range.
Do.....	850- 950	Preferred Range.

The temperatures given above for the quench zone inlet stream are those for operations when a preheating zone is not provided thereabove. When a preheating zone is provided the solid material inlet temperature to the quench zone is somewhat lower than that given in the above table, for example the preferred inlet temperature may be of the order of 650-850° F. The pressure in the coking zone is usually of the order of nearly atmospheric up to about 30 pounds per square inch gauge but may range up to about 200 pounds per square inch in some operations. The temperature ranges given above are for the low pressure operation. The pressure in the catalytic reactor is usually of the order of 5-30 pounds per square inch but may in some instances be substantially higher. The relative rates of heat carrying material and reactant flow in the coking, quench and preheating zones is purely a question of thermal balance, the heat carrying material being regulated in rate of flow and inlet temperature to carry substantially the entire heating or cooling load in the zone in question. In the catalytic reactor the reactant space velocity may range from about 0.5 to 10.0 volumes of oil charge per hour (measured as a liquid at 60° F.) per volume of catalyst in the reaction zone. The catalyst to oil ratio may vary from about 1 to 10 parts of catalyst per part of oil charge per hour by weight.

The specific examples of operation and details of apparatus arrangement and process technique given hereinabove are intended as exemplary and should not be construed as limiting the scope of this invention except as it may be limited by the following claims.

I claim:

1. A method for conversion of high-boiling liquid hydrocarbons to lower-boiling hydrocarbon products which comprises: maintaining a substantially compact bed of granular solid heat carrying material in an upright confined zone, withdrawing a stream of solid material from the lower section of said zone to cause downward movement of the solid material in said bed, introducing high-boiling liquid hydrocarbons into said bed at an intermediate level along its length to contact said heat carrying material and to effect a partial

conversion of said liquid hydrocarbons to a gasiform product containing lower boiling hydrocarbons and a small amount of entrained unvaporized liquid hydrocarbons and with the deposition of a carbonaceous coky material on the heat carrying material, said liquid hydrocarbons being introduced at a temperature below that required for its partial conversion, introducing heated solid heat carrying material into an intermediate portion of said bed near the level of liquid hydrocarbon introduction at a temperature above that of the liquid hydrocarbons and sufficiently high to supply the heat required for effecting the vaporization and said partial conversion of said liquid hydrocarbons, supplying cooler solid heat carrying material to the surface of said bed at a temperature controlled at a level suitable for quenching the conversion reaction and for condensing some but only a small portion of said gasiform product, passing said gasiform product containing entrained liquid upwardly through said bed to contact said cooler solid material whereby the conversion reaction is substantially inhibited and a small portion of the gasiform product is condensed and deposited upon the solid material along with said entrained liquid, withdrawing the gasiform product from the upper section of said zone and passing it into contact with a finely divided adsorbent catalyst under conditions of temperature and pressure suitable for effecting further conversion to gasiform, gasoline containing products.

2. A method for catalytically converting high boiling petroleum fractions containing constituents which decompose below their boiling temperatures which comprises, maintaining a substantially compact column of granular heat carrying material in a confined upright zone, introducing a high boiling petroleum fraction as a liquid into said column at an intermediate level along its length to effect thermal coking of said petroleum fraction to a gasiform product containing a small amount of relatively high boiling entrained liquid and to a coky deposit on the heat carrying material, introducing a first stream of heated inert heat carrying material into said column shortly above the level of liquid hydrocarbon introduction at a temperature above that of said petroleum fraction and above the average coking temperature and sufficiently high to supply the heat required for the coking reaction, introducing a second stream of substantially cooler inert heat carrying material onto the surface of said column, said cooler heat carrying material being at a temperature above that at which most of said product will condense, withdrawing used heat carrying material from the bottom of said column to cause downward movement of the heat carrying material through said confined zone, passing the gasiform product formed in said coking reaction along with the entrained high boiling liquid hydrocarbons upwardly within said column to contact progressively hotter heat carrying material until it reaches the level of the heated material introduction and then to contact progressively cooler heat carrying material in the upper portion of said column whereby the entrained liquid hydrocarbons are left behind on the heat carrying material as the gasiform products leave the surface of said column, and passing the gasiform products substantially free of entrained liquid hydrocarbons into contact with a finely divided catalyst to effect the catalytic cracking conversion thereof to lower boiling gasoline containing products.

3. A method for conversion of petroleum residuums to high antiknock gasoline comprising, maintaining a substantially compact column of granular, petroleum coke, in an elongated, confined zone, supplying heated granular coke into said column at an intermediate level to maintain the column temperature below said level of introduction at a suitable range of coking temperatures below about 1200° F., supplying granular coke onto the surface of said column at a temperature substantially below that of the heated coke introduction and below about 1000° F., withdrawing used granular coke from the bottom of said column, introducing petroleum residuum charge in the liquid phase into said column below the level of heated coke introduction to effect coking of said charge to lower boiling gasiform hydrocarbons, said petroleum charge being introduced at a temperature insufficient to effect its coking so that the heat required for the coking is supplied by said granular coke passing the gasiform hydrocarbons upwardly through said column along with a small amount of non-vaporized liquid hydrocarbons to contact first the heated coke and later the cooler coke in the upper section of said column, whereby the gasiform product is cooled to a temperature substantially below the highest level to which it was heated by said heated coke, whereby the entrained liquid hydrocarbons are deposited on said coke, withdrawing the gasiform product from said column below the temperature required for its catalytic cracking conversion temperature and heating it to said catalytic cracking conversion temperature which is above about 800° F., passing the heated gasiform product into contact with a granular cracking catalyst to effect its further conversion to a high antiknock gasoline containing product and separating said gasoline containing product from said catalyst.

4. A method for conversion of petroleum residuums to high antiknock gasoline comprising, maintaining a substantially compact column of granular, substantially inert heat carrying material in an elongated, confined zone, introducing petroleum residuum charge as a liquid into the lower portion of said column to effect coking thereof at a suitable range of coking temperatures to provide a stream of lower boiling hydrocarbons in the gaseous phase in which is entrained some non-vaporized liquid hydrocarbons, passing said stream upwardly into a cooler and intermediate portion of said column wherein it is cooled by contact with the heat carrying material to a quench temperature at which the coking reaction is substantially inhibited and the entrained liquid is deposited on the solid heat carrying material, said quench temperature being substantially below the highest temperature reached in said lower portion of said column and being below the suitable catalytic cracking temperature, passing the cooled stream, substantially free of entrained liquid up through an upper portion of said column wherein its temperature is raised to a suitable temperature for its catalytic conversion which is below the maximum temperature reached by said stream in said lower portion of the column, withdrawing the heated stream from said column and passing it into contact with a finely divided catalyst to effect its cracking conversion to a gasoline containing product in a separate zone and effecting a separation of said product for the used cracking catalyst, introducing a first portion of inert solid heat carrying material into said column at a level shortly above

that of the liquid residuum charge and at a temperature substantially above the average coking temperature in said lower portion of said column, introducing a second portion of said heat carrying material into said column at an intermediate level below its surface and above the level of said first portion and at a quench temperature substantially below that of said first portion, controlling the rate and temperature of introduction of said second portion of heat carrying material to effect the quenching of said stream of gasiform hydrocarbons as aforesaid, introducing a third portion of said heat carrying material onto the surface of said column at a temperature substantially above that of said second portion, controlling the rate of introduction of said third portion to effect heating of said gasiform stream to said suitable catalytic cracking conversion temperature and withdrawing said inert heat carrying material at a controlled rate from the bottom of said column.

5. A method for conversion of petroleum residuums to high antiknock gasoline comprising, maintaining a substantially compact column of granular substantially inert heat carrying material in an elongated, confined zone, introducing petroleum residuum charge as a liquid into the lower portion of said column to effect coking thereof at a suitable range of coking temperatures to provide a stream of lower boiling hydrocarbons in the gaseous phase in which is entrained some non-vaporized liquid hydrocarbons, passing said stream upwardly into a cooler and intermediate portion of said column wherein it is cooled by contact with the heat carrying material to a quench temperature at which the coking reaction is substantially inhibited and the entrained liquid is deposited on the solid heat carrying material, said quench temperature being substantially below the highest temperature reached in said lower portion of said column and being below the suitable catalytic cracking temperature, passing the cooled stream, substantially free of entrained liquid up through an upper portion of said column wherein its temperature is raised to a suitable temperature for its catalytic conversion which is below the maximum temperature reached by said stream in said lower portion of the column, introducing a first portion of inert solid heat carrying material into said column at a level shortly above that of the liquid residuum charge and at a temperature substantially above the average coking temperature in said lower portion of said column, introducing a second portion of said heat carrying material into said column at an intermediate level below its surface and above the level of said first portion and at a quench temperature substantially below that of said first portion controlling the rate and temperature of introduction of said second portion of heat carrying material to effect the quenching of said stream of gasiform hydrocarbons as aforesaid, introducing a third portion of said heat carrying material onto the surface of said column at a temperature substantially above that of said second portion, controlling the rate of introduction of said third portion to effect heating of said gasiform stream to said suitable catalytic cracking conversion column, withdrawing used heat carrying material at a controlled rate from the bottom of said column, passing a part of the used heat carrying material through a separate heating zone wherein it is heated to a temperature suitable for reuse, utilizing a part of the heated heat carrying material to supply said first portion

of heat carrying material introduced into said column, utilizing the remainder of the heated heat carrying material to supply said third portion introduced onto said column, passing the remainder of the used heat carrying material through a separate heat exchange zone wherein it is regulated to a suitable quench temperature and utilizing the latter heat carrying material to supply said second portion introduced into said column, withdrawing the heated stream from said column and passing it into contact with a finely divided catalyst to effect its cracking conversion to a gasoline containing product in a separate zone and effecting a separation of said product from the used cracking catalyst.

6. A method for conversion of petroleum residuums to high antiknock gasoline comprising, maintaining a substantially compact column of granular, substantially inert heat carrying material in an elongated, confined zone, introducing petroleum residuum charge as a liquid into the lower portion of said column to effect partial conversion and gasification thereof at an elevated temperature suitable for pyrolytic cracking of the residuum to form a stream of lower boiling gasiform hydrocarbons containing a small amount of entrained non-gasified liquid hydrocarbons, passing said stream upwardly into a cooler and intermediate portion of said column wherein it is cooled by contact with the heat carrying material to a quench temperature at which the pyrolytic cracking reaction is substantially inhibited and a minor fraction of the stream is condensed and deposited on the solid heat carrying material along with the liquid entrained from the lower portion of said column, said quench temperature being substantially below the highest temperature reached in said lower portion of said column and being below the suitable catalytic cracking temperature, passing the cooled stream, substantially free of entrained liquid up through an upper portion of said column wherein its temperature is raised to a suitable temperature for its catalytic conversion which is below the maximum temperature reached by said stream in said lower portion of the column, withdrawing the heated stream from said column and passing it into contact with a finely divided catalyst to effect its cracking conversion to a gasoline containing product in a separate zone and effecting a separation of said product from the used cracking catalyst, introducing a first portion of inert solid heat carrying material into said column at a level shortly above that of the liquid residuum charge and at a temperature substantially above the average pyrolytic cracking temperature in said lower portion of said column, introducing a second portion of said heat carrying material onto the surface of said column at a temperature at least equal to said suitable catalytic cracking temperature and substantially below that of said first portion of heat carrying material, introducing a third portion of said heat carrying material into said column at a level intermediate the levels of introduction of said first and second portions of heat carrying material and at a quench temperature which is below that of said second portion but insufficiently low to condense most of said stream of lower boiling hydrocarbons formed in said lower portion of said column, and withdrawing said inert heat carrying material at a controlled rate from the bottom of said column.

7. A method for conversion of high boiling liquid petroleum fractions to a lower boiling gaso-

line containing conversion product comprising, maintaining a substantially compact column of granular heat carrying material of low catalytic activity extending upwardly through a lowermost pyrolytic conversion zone, an intermediate quenching zone and an upper preheating zone, withdrawing heat carrying material from the bottom of said column to cause downward movement of the heat carrying material through all of said zones, heating a portion of the withdrawn heat carrying material to a temperature suitable for supporting the pyrolytic cracking reaction and supplying it into said column at a level corresponding to the upper portion of said pyrolytic conversion zone, introducing a high boiling liquid hydrocarbon fraction into said pyrolytic conversion zone below the conversion temperature and substantially below the temperature of said heat carrying material to contact said heat carrying material, whereby it undergoes pyrolytic conversion to a partially converted intermediate product existing mainly in the gaseous phase but containing small amounts of non-vaporized liquid hydrocarbons, subjecting a second portion of the heat carrying material withdrawn from said column to cooling to effect reduction in its temperature to a level suitable for substantially quenching the pyrolytic cracking reaction but above that which would cause condensation of more than about 15 percent of said intermediate product and introducing this latter material into said column at an intermediate level corresponding to the upper section of said quench zone, passing the gasiform intermediate product with entrained liquid upwardly from said pyrolytic conversion zone into contact with the cooler heat carrying material in said quench zone whereby the reaction is substantially inhibited and the entrained liquid is deposited onto the heat carrying material, adjusting the temperature of a third portion of the heat carrying material withdrawn from said column to a level intermediate that of said first and second portions and at least equal to a suitable temperature for the catalytic cracking conversion of said intermediate product and supplying said third portion onto the surface of said column which corresponds to the top of said upper heating zone, passing the quenched intermediate gasiform product upwardly from said quench zone into contact with the hotter heat carrying material in said heating zone whereby it is heated to a suitable temperature for its catalytic cracking conversion and passing the heated intermediate product into contact with a suitable finely divided adsorbent cracking catalyst in a separate, confined zone to effect its conversion to a gasoline containing product.

8. A method for coking high boiling petroleum fractions to lower boiling products comprising, maintaining a substantially compact column of granular heat carrying material of low catalytic activity extending through a lower coking zone and an upper quench zone, withdrawing heat carrying material from the bottom of said column to cause downward movement of the heat carrying material through all of said zones, heating a portion of the withdrawn heat carrying material to a temperature suitable for supporting the coking reaction and supplying it into said column at a level corresponding to the upper portion of the coking zone, introducing a high boiling liquid petroleum fraction into said coking zone at a temperature below that of said heat carrying material and insufficient to provide the heat for said coking reaction to contact said heat carrying ma-

terial therein, whereby it undergoes coking to form a lower boiling gaseous product existing mainly in the gaseous phase but containing small amounts of high-carbon-residue liquid hydrocarbons, subjecting a second portion of the heat carrying material withdrawn from said column to cooling to effect reduction in its temperature to a level suitable for substantially quenching the coking reaction but above that which would cause condensation of more than about 15 percent of said lower boiling product and introducing this latter material into said column at a level corresponding to the upper section of said quench zone, passing the lower boiling product with entrained liquid upwardly from said coking zone into contact with the cooler heat carrying material in said quench zone whereby the reaction is substantially inhibited and the entrained high-carbon-residue liquid is deposited upon the heat carrying material, withdrawing said lower boiling product in gaseous form and substantially free of entrained liquid hydrocarbons from the upper section of said column at a temperature above that at which more than 15 percent of the product condenses.

9. A method for conversion of petroleum residua to high antiknock gasoline comprising, maintaining a substantially compact column of granular, substantially inert heat carrying material in an elongated, confined zone, introducing petroleum residuum charge as a liquid into the lower portion of said column to effect partial conversion and gasification thereof at an elevated temperature suitable for pyrolytic cracking of the residuum to form a stream of lower boiling gasiform hydrocarbons containing a small amount of entrained non-gasified liquid hydrocarbons, passing said stream upwardly into a cooler and intermediate portion of said column wherein it is cooled by contact with the heat carrying material to a quench temperature at which the pyrolytic cracking reaction is substantially inhibited, said quench temperature being below a suitable catalytic cracking temperature, passing the cooled stream up through an upper portion of said column wherein its temperature is raised to a level suitable for catalytic conversion of the hydrocarbons, withdrawing the heated stream from said column and passing it into contact with a suitable catalyst to effect its cracking conversion to a product containing high octane gasoline and effecting separation of said product from the cracking catalyst, introducing a first portion of inert solid heat carrying material into said column at a level shortly above that of the liquid residuum charge and at a temperature substantially above the average pyrolytic cracking temperature in said lower portion of said column, introducing a second portion of said heat carrying material onto the surface of said column at a temperature at least equal to said suitable catalytic cracking temperature and substantially below that of said first portion of heat carrying material, introducing a third portion of said heat carrying material into said column at a level intermediate the levels of introduction of said first and second portions of heat carrying material and at a quench temperature which is below that of said second portion but insufficiently low to condense most of said stream of lower boiling hydrocarbons formed in said lower portion of said column, controlling the rate of introduction of the first and third portions of the heat carrying material into said column to supply the heat for said pyrolytic re-

action and to supply the cooling capacity for the product quenching respectively, withdrawing heat carrying material from the bottom of said column at a rate which is in excess of the total rate of supply of said first and third portions by an amount approximately equal to the required rate of supply of said second portion to effect the reactant preheating and supplying said second portion onto the surface of said column at a rate adjusted to maintain constant the surface level of said column.

10. A method for effecting high temperature conversions of high boiling petroleum fractions comprising maintaining a substantially compact column of granular heat carrying material in a confined upright zone, introducing a high boiling petroleum fraction as a liquid into said column at an intermediate level along its length to effect thermal coking of said petroleum fraction to a gasiform product containing a small amount of relatively high boiling entrained liquid and to a coky deposit on the heat carrying material, introducing a first stream of heated inert heat carrying material into said column shortly above the level of liquid hydrocarbon introduction at a temperature above the average coking temperature and at a rate positively controlled to effect supply as sensible heat in the heat carrying material the heat required for the coking reaction, introducing substantially cooler heat carrying material into said column at a higher level therein spaced substantially below the column surface, said cooler heat carrying material being at a temperature substantially below said coking temperature and the rate of said cooler heat carrying material introduction being positively controlled to effect quenching of the gasiform product flowing up from the lower and hotter portion of said column and the deposition of entrained liquid on the solid material, withdrawing heat carrying material from the bottom of said column at a rate substantially above the combined rates of introduction of said first and second streams, flowing by gravity a stream of heat carrying material existing at a temperature intermediate said first and second streams from an external supply zone down onto the surface of said column to maintain said column continuously replenished and to supply into the upper portion of said column sufficient heat to raise the temperature of the quenched gasiform product to a level intermediate the coking and quench temperatures and withdrawing the reheated gasiform product from the upper portion of said column.

11. A method for coking high boiling petroleum fractions to lower boiling products comprising, maintaining a substantially compact column of granular heat carrying material of low catalytic activity extending through a lower coking zone and an upper quench zone, withdrawing heat carrying material from the lower section of said column to cause downward movement of the heat carrying material through all of said zones, supplying heat carrying material at a temperature suitable for supporting the coking reaction and supplying it into said column at a level corresponding to the upper portion of the coking zone, introducing a high boiling liquid petroleum fraction into said coking zone at a temperature below that of said heat carrying material and insufficient to provide the heat for said coking reaction to contact said heat carrying material therein, whereby it undergoes coking to form a lower boiling gaseous product existing mainly in the gaseous phase but containing small amounts of

high-carbon residue liquid hydrocarbons, introducing a second portion of solid heat carrying material into said column at a level corresponding to the upper section of said quench zone at a temperature level suitable for substantially quenching the coking reaction and also condensing a minor fraction of but not more than about 15 percent of said lower boiling product, passing the lower boiling product with entrained liquid upwardly from said coking zone 10 into contact with the cooler heat carrying material in said quench zone, whereby the reaction is substantially inhibited and a minor fraction of the lower boiling product stream is condensed and deposited on the solid heat carrying material along with said entrained high-carbon-residue liquid, withdrawing the remaining lower

5 boiling product in gaseous form and substantially free of entrained liquid hydrocarbons from the upper section of said column at a temperature above that at which more than 15 percent of the product condenses.
